UNITED STATES PATENT OFFICE.

RUSSELL K. COLLINS, OF FORT WORTH, TEXAS, ASSIGNOR, BY MESNE ASSIGNMENTS, TO COLLINS PROCESS, INC., OF WILMINGTON, DELAWARE, A CORPORATION OF DELAWARE.

EXPANSION PROCESS AND APPARATUS FOR REFINING HYDROCARBON MATERIALS.

Application filed May 23, 1922. Serial No. 563,136.

This invention relates to a new and improved process for the refining of hydro-carbon materials.

A further object of the invention is the provision of an improved process for the refining of hydro-carbon fluids by destructive distillation, having particular regard for the treatment of hydro-carbon vapors according to the chemical, thermo-dynamic, and 10 mechanical laws of physical conversion.

A further object of the invention is the provision of an improved process for the refining of hydro-carbon materials, according to an expansion method, in which certain 15 hydro-carbon vapors are initially provided in pre-expanded state by distillation, and separated and treated in such manner as to most effectively release the constituent atoms thereof.

20 A further object of the invention is the provision of an improved expansion process for the refining of hydro-carbon materials, providing for the separation of the lighter, and heavier fractions of a resultant hydro-carbon product, and including an improved 25 arrangement for treating and further refining the heavier fraction.

A further object of the invention is the provision of an improved process for the 30 refining of hydro-carbon material, including an improved method of treating hydro-carbon vapors with "fixed" hydro-carbon gases to increase the yield of gasoline distillate from a given body of oil.

35 A further object of the invention is the provision of an improved apparatus for the refining of hydro-carbon material, which includes an improved method of treating and revaporizing a heavier fraction after destructive distillation, and co-mingling the 40 revaporized fraction with an initial product, in such manner as to increase the yield of a desired distillate.

A further object of the invention is the 45 provision of an improved apparatus for the refining of crude petroleum oil according to an expansion process, so arranged as to utilize the products of fuel combustion in the heating of the resultant products throughout the various steps of the process.

50 Other objects and advantages of this process will of course, be apparent during the following detailed description.

In the accompanying drawings, forming a

part of this specification, and wherein similar reference characters designate corresponding parts throughout the several views, 55

Figure 1 is a side elevation of a part of the apparatus used in the refining of hydro-carbon materials according to the improved 60 expansion process.

Figure 2 is a diagrammatic view showing the treatment of a hydro-carbon material in the various steps of the expansion process.

Figure 3 is a fragmentary view, partly in 65 section, showing the expander and its associated parts.

Figure 4 is a view, partly in section, showing a dephlegmator used as a part of the improved apparatus for refining of hydro-carbon products. 70

In the drawings, wherein for the purpose of illustration is shown the preferred embodiment of this invention, the letter A generally designates the improved apparatus 75 for refining of hydro-carbon materials, and includes a still B; expander apparatus C; furnace D; dephlegmator E; back trap convertor or rerun still F; condenser G; receiving house H; pump house K; receiving tank 80 L; and "fixed" gas tank M.

Referring to the still B, the same is preferably of the cylindrical horizontal type, provided with the ordinary accessories, and including a dome 10 intermediate its ends 85 into which a vapor line 11 communicates and extends horizontally for connection to the expander C.

The improved expander C, which is more 90 specifically described and claimed in my co-pending application filed May 8, 1922, Serial No. 561,925, includes a cylindrical shaped casing 15 which is vertically positioned, and includes the side walls 16; top wall 17; and bottom wall 18. A pipe 19 communicates the vapor line 11 with the chamber 20 of the casing 15 adjacent the bottom wall 18, for supply of vapor to the chamber 20 in a manner which will be subsequently described. The casing 15 is mounted upon a 95 conical shaped housing 21, which provides a heat chamber 22 therebelow; said housing 21 likewise being provided as a support for the back trap convertor F in a manner which will be subsequently described in detail. 100 Tubes or flues 25 are provided in the chamber 20 of the casing 15, arranged in parallel 105 relation longitudinally thereof, and sup-

ported at their ends by the top and bottom plates 17 and 18 respectively of said casing 15, so that said tubes open at their lower ends into the chamber 22 of the housing 21, and at their upper ends into the chamber 27 of a stack 28. Perforated nickel screens 29 are provided in the chamber 20 arranged as baffle plates therein, and suitably affixed to the inside of the casing walls 16 so that the chamber 20 is subdivided into a plurality of compartments; the baffles 29 being arranged in parallel relation to the top and bottom walls 17 and 18. An outlet pipe 30 leads from the casing 15 adjacent the top wall 17 to the dephlegmator E for the purpose of conveying vapor thereto. A pipe section 31 is provided, communicating the vapor line 11 adjacent the connection 19 thereof with the line 30 leading to the dephlegmator E; said pipe section 31 having a cut-off valve 32 therein which may be regulated for closing when it is desired to divert vapors from still B into the expander C, as will be the case during the operation of the apparatus A according to the expansion process. A valve 35 may be provided in the pipe connection 19, which is normally open, although the same may be closed for cutting off communication of the vapor line 11 with the expander C. If desired, a check valve 37 may be provided in the vapor line 11, as is shown in the diagrammatic illustration of the improved process, in order to prevent sudden back pressure from forming on the vaporizer or still B. An automatic pressure release valve 38 may be provided in the outlet pipe 30 adjacent the expander C, for the purpose of regulating any pressure which might exist within the expander, altho such pressure is normally very low.

The furnace D is provided with its main heating chamber 39 below the vaporizer or still B, and extends longitudinally thereof; the fire grate 40 being positioned at the forward end of said still B. A passageway 41 is, however, provided in the foundation 42 in which the furnace D is supported; said passageway 41 leading beneath the expander C and communicating into the chamber 22 of the housing 21 thereof. Draft control flues 43 may be provided in the passageway 41 of the foundation 42 and beneath the expander, said flues being provided for the purpose of controlling the amount of products of combustion which may pass from the furnace chamber 39 through the passageway 41 into the chamber 22 above described. It is obvious that by such an arrangement, the products of combustion from the fuel within the chamber 39 are not only utilized for heating the still B, but pass into the chamber 22 of the expander housing 21 for heating the back trap converter F; said products of combustion further passing upwardly through the various expander flues 25 for

heating the hydrocarbon product within the casing chamber 20. The waste products of combustion finally pass through the stack 28 after being utilized for heating of the still B, back trap converter F, and expander 70 casing 15.

Referring to the dephlegmator tower E, the same is provided for receiving the hydro-carbon vapor after destructive distillation in the expander C, performing the function of separating the lighter and heavier fractionates of the hydro-carbon product as is well known to those skilled in the art. The dephlegmator E includes the cylindrical shaped casing 45, which comprises the side walls 47; top wall 48; and bottom wall 49; said top and bottom walls 48 and 49 preferably being of convex formation. The pipe section 30 for conducting of vapors from the expander C has communication with the inlet opening 50 in the casing 45, just upwardly of the bottom wall 49, as is illustrated in Figures 1 and 4 of the drawings. An opening 51 is provided, adjacent the top wall 48, through the side wall of the casing 45, for outlet of the lighter fraction in vapor form from the dephlegmator E. A plurality of horizontal perforated baffle plates 52 are provided within the chamber 53 of the casing 45, to subdivide the same into a plurality of compartments 54 intermediate the inlet and outlet openings 50 and 51 respectively. Each of the compartments 54 is provided with a frusto-conical shaped baffle plate 55 of sheet material, which is affixed about its entire major circumference to the interior of its compartment 54. Each baffle plate 55 is provided with a relatively large central opening 56 therein for outlet of the uncondensed fraction into the next succeeding compartment 54.

Vapor entering the dephlegmator E from the pipe line 30 enters the lower compartment 57 just below the baffle plate 52. This vapor, as will be hereinafter more fully set forth has been converted so that the constituent parts thereof are released and ready for dephlegmation. The vapors entering from the pipe 30 will first pass through the perforations of the lower baffle plate 52, and ride over the inner surface of the conical baffle plate 55 in the lowermost compartment 54. Due to the fact that the constituent parts of the vapor are ready for the dephlegmation action, the heavier fractionate will condense upon the inside of the lower baffle 55, as is well known, and drop into the chamber 57. The remaining vapor will pass through the opening 56 in the lower baffle plate 55, and be baffled in its upward passage by means of the second upwardly positioned perforated baffle plate 52, so that some of the heavier fractionate will condense thereon and drop onto the exterior 130

surface of the lower conical shaped baffle plate 55, where said heavier fractionate will flow downwardly into the circumferential groove in the lower compartment 54 about 5 the baffle plate 55. The vapor arising into the second upper compartment 54 likewise is baffled upon the second conical shaped baffle plate 55, and some of the heavier fractionate will condense inwardly thereon and 10 after dropping therefrom will flow into the passageway about the lower baffle plate 55 as above mentioned. The vapor in thus arising toward the outlet opening 51 will be successively baffled against the various conical shaped baffle plates 55, so that heavier 15 fractions having varying boiling points will be caught in each of the compartments 54 about the circumferential groove provided by the baffle plates 55. The condensed fractionate so caught in the compartments 54 may be led off in any desired manner, either 20 individually or combined. In the improved expansion process, herein described, it is preferred that a pipe line 59 be provided exteriorly of the casing 45, having connection with the various compartments 54 by means 25 of the couplings 60, just upwardly of the circumferential connections of each of the conical shaped baffle plates 55 with the casing 45, in order that the material condensed 30 in the compartment 54 may be led into the lowermost chamber 57 of the dephlegmator E, where the combined condensed fractionate may be conveyed, as by gravity, through 35 the drain pipe 62 into an end of the back trap converter F. If desired, a man hole cover 63 may be provided in the top wall 48 for access to the chamber 58.

Referring to the back trap converter F, 40 the same is transversely mounted in the housing 21 of the expander apparatus C above described, so that the ends thereof extend exteriorly of the housing 21, although the main body portion of the back trap converter casing 64 extends through the chamber 22 for receiving the heat therefrom. The chamber 65^a of the elongated converter casing 64 is adapted for receiving the condensed fractionate from the dephlegmator E 45 through the drain tube 62, which is connected in one end thereof as is illustrated in the drawings. A pipe line 65 likewise communicates with the converter chamber 65^a, adjacent the fractionate inlet tube 62; said line 65 being provided for leading "fixed" 50 hydro-carbon gas into the converter F for a purpose which will be subsequently described. Superheated steam may be conveyed from a boiler 67 through conduits 68 55 for inlet into the vaporizer or still B as at 69; said conduit 68 leading for communication with the back trap converter F at an end opposite that to which the gas line 65 is connected. The inlet of superheated 60 steam to the chamber 65^a may be controlled 65 in the conduit 68 by means of a valve 70. A pressure gauge 71 may be appropriately carried by the converter casing 64. Likewise, a drain tube or cock 72 may be provided therein. The chamber 65^a is preferably provided with a plurality of perforated baffle plates 73 arranged therein in staggered relation, so that the flow of materials within the chamber 65^a is baffled for thorough admixing thereof in order to revaporize the 70 fractionate therein and suitably treat the same, so that it may arise through the perforated tube 76 into the chamber 20 of the expander C for admixing with the vapors therein in order to provide proper reaction 75 of the hydro-carbon vapors.

The lighter fractions emanating from the dephlegmator E in the form of vapor are led through the conduit 75 into the condenser G, which is of any approved type, such as 80 the standard worm and water box construction. The distilled product issues from the condenser G into the receiving housing H through a pipe line 77. If desired, a water trap 78 may be positioned in the pipe line 85 77, operating in an effective manner for separation of water from the condensed fraction. The receiving house equipment is also of conventional type, and wherein the fixed 90 gases are drawn into the gas header 78^a by 95 means of a vacuum maintained therein by the gas compressor 79. The condensed distillate passes through the run down lines 80 and into the receiving tank L. The gas compressor 79 is preferably operated by 100 steam from the line 81, which is in the super heated steam conduit 68 above described. The "fixed" gases are ultimately discharged 105 into the gas tank M, and light hydro-carbon distillates similar to those known as "casing 110 head" gasoline are here collected by means of a drip trap 83. A blower 84 may be positioned in the pump house K for conducting 115 of the "fixed" gases from the tank M therethrough into the back trap converter F 120 through the conduit 65.

Referring more particularly to the process for treating of hydro-carbon materials, the crude petroleum is disposed, in any appropriate manner, within the still B and heated 125 therein from the products of combustion within the fuel chamber 39. The heating of the crude petroleum within the still B continues until the liquid molecules release their constituent parts above the liquid mass, in the form of vapor. The vapor in its pre-expanded state then passes into the vapor line 11. The conventional practice in further treatment of these vapors is that of passing the vapors through super heated 130 flues or coils which in addition to resulting in an enormous waste of the hydro-carbon materials, is dangerous to operators and necessitates the continued installment of new apparatus with the attendant expense and 135

the loss of operating time, as is well known. Complete separation of the constituent parts of the hydro-carbon vapors cannot be obtained within the still B, due to the necessary confinement of the vapors therein by reason of constriction of the space and consequent pressures. The vapors issuing from the vapor line into the expander casing 15 undergo a mechanical expansion by reason of the removal of their space restriction, and further expansion is likewise effected by the application of heat within the expander chamber 20; said heat passing off from the flues 25. The vapors entering the chamber 20 spiral upwardly about the flues 25 in violent manner. The volume of gas within the chamber 20 is thus pierced, so to speak, with adjacently positioned heating flues for the even and thorough heating of the whole mass of the vapor within the expander C in the quickest manner possible. The mechanical and thermo-dynamic expansion of the vapors in the chamber 20 continues until molecular conversion takes place, releasing the lighter and more volatile constituents from the heavier constituent molecules thereof. The resultant product flows into the dephlegmator E, where the same is treated in the manner above described, and the heavier fractionate emanating from the expander C is condensed for drain into the back trap convertor F. Due to the removal of the space restriction in the expander, so that the hydrocarbon in the vapor phase may undergo a mechanical expansion, in combination with a thorough and uniform heating of the vapor to further expand the same, molecular conversion is quickly accomplished, without the necessity of prolonged treatment in the expander; it being thus possible to quickly treat a large quantity of the product in the vapor phase to produce the result herein defined.

It is conventional practice to rerun the heavier fractionate after dephlegmation with separate heatings to vaporize, crack, and condense, all of which operations are independent of the original process. In the improved expansion process of refining hydro-carbon materials, the heavier distilled fractionate in the back trap converter is combined with superheated steam which is injected therein by means of the conduit 68, and the same is likewise associated in the back trap converter with the "fixed" gases forced therein through the conduit 65 as hereinbefore described. The vapor issuing from the perforated tube 76 into the chamber 20 of the expander C cooperates with the vapor in the chamber 20 which has passed therein from the vapor line 11. The process of conversion within the expander continues in conjunction with the process of hydrogenation which is brought about by the steam introduced into the expander from

the vaporizer by way of the vapor line, and also from the back trap converter, in company with the "fixed" gases and other vapors generated therein. The breaking down of the hydro-carbon being treated within the expander into "fixed" gases and solid carbon is thus prevented, and the formation of the desired fractions is facilitated by the introduction of permanent or "fixed" gases and the superheated steam from the boiler 67. The reactions within the expander are of such character as to produce a maximum yield of the desired fractions. Since there is an excess of "fixed" gas within the expander chamber 20, there need be no breaking down of the hydro-carbon gases of the initial material supplied from the vapor line 11. On the contrary, it has been found in actual practice that the tendency for the new gaseous formation resulting from combining of the vapors from the line 11 and the vapor from the back trap convertor, absorb some of the "fixed" gases coming from the back trap convertor, and thereby augmenting the yield of the lighter group of hydro-carbon distillates. Thus, it can be seen that the term "fixed" gas is herein used to designate a hydrocarbon product which still contains some valuable component, and which valuable component is absorbed during the treatment as herein described.

It will be noted that the back trap converter performs a function which is essentially that of a small rerun still, but of greatly increased efficiency, since the distillates that it converts or reruns are delivered in relatively small quantities from the dephlegmating tower without the necessity of putting the rerun through an independent conversion process. A check valve 85 may be provided in the drain line 62 to prevent back pressures from the convertor F reaching the dephlegmator chamber 53.

No mechanical stirrers or coke removers are needed in the expansion process herein described, as no total decomposition takes place, except at the will of the operator. For cleaning and inspection purposes, a man hole 86 may be provided in the expander chamber 15, as is illustrated in Figure 1 of the drawings.

From the foregoing description of the apparatus and process of the invention herein shown and described, it can be seen that considerable fuel conservation will result in this treatment of the various hydro-carbon materials, in that products of combustion in the furnace D are utilized for heating the still B, expander C, and back trap convertor F. It is an outstanding feature of this invention that the final conversion of the hydro-carbon material for releasing of the lighter and heavier constituents thereof is effected in the vapor phase, at a time when the same is completely separated from the

- liquid hydro-carbon material. This is an improvement, taken in conjunction with the other characteristics of the expander C, as it has been proven that in processes which 5 retain the vaporized hydro-carbon within the container also occupied by the liquid hydro-carbon and treated to the point of conversion, the resultant product will be relatively poor, and of low yield.
- 10 Various changes in the shape, size, and arrangement of parts of the apparatus herein shown and described for the refining of various hydro-carbon materials may be made, without departing from the spirit of this invention or the scope of the claims.
- I claim:
1. The process of treating petroleum, which consists in distilling a hydro-carbon material in a still to provide a vapor, conducting said vapor into an expansion chamber, heating the vapor in said expansion chamber to a conversion point to release the constituent parts thereof, passing the released constituent parts through a dephlegmator to separate the lighter and heavier fractions, conducting the heavier fractions to a rerun chamber, treating said heavier fractions in the rerun chamber with superheated steam and a "fixed" hydro-carbon gas, heating the resultant product in the rerun chamber to form a vapor and conducting the vapor from said rerun chamber to said expansion chamber for conversion therein with the vapor emanating from said 35 still.
2. The process of treating hydro-carbon materials which consists in distilling a hydro-carbon material in a still to provide a vapor product, conducting the vapor product into an expansion chamber, heating the vapor product in said expansion chamber to a conversion point in order to release the constituent parts thereof, passing the constituent parts through a dephlegmator to separate the lighter and heavier fractions thereof, conducting the heavier fraction to a rerun chamber, treating the heavier fraction in said rerun chamber with superheated steam and "fixed" hydro-carbon gases, heating the 40 resultant product in said rerun chamber with the products of combustion passing off after heating of the still to form a vapor product within said rerun chamber, and conducting the vapor product from said rerun chamber to said expansion chamber for conversion therein with the vapor therein emanating from said still.
3. The process of treating petroleum which consists in distilling a hydro-carbon material in a still to provide a vapor product, injecting superheated steam with said vapor product from said still, conducting the vapor product and superheated steam into an expansion chamber, heating the vapor product within said expansion chamber to a 45 conversion point in order to release the constituent parts thereof, passing the constituent parts through a dephlegmator to separate the lighter and heavier fractions thereof, conducting the heavier fractions to a rerun chamber, treating said heavier fractions in the rerun chamber with superheated steam and fixed hydro-carbon gases, heating the resultant product in the rerun chamber to form a vapor product, conducting said vapor product to the expansion chamber for conversion therein with the vapor emanating from said still, and passing the lighter fractions from the dephlegmator for condensation.
4. An apparatus for the treatment of hydro-carbon materials comprising a still having a chamber therein for receiving hydro-carbon materials, an expander including a chamber in communication with said still chamber, means for heating said still chamber and expander whereby a vapor product may pass from said still chamber to said expansion chamber for conversion in the latter, a dephlegmator for receiving the converted product from said expander chamber, a back trap converter for receiving the heavier fraction from said dephlegmator, means for treating the fraction in said back trap converter for supplying a vapor product therefrom to said expander chamber, and condensing apparatus for receiving the lighter fraction from the dephlegmator.
5. An apparatus for the treatment of hydro-carbon materials comprising a still including a chamber, an expander including a chamber in communication with said still, a dephlegmator communicating with said expander chamber, a back trap convertor communicating with said dephlegmator and expander chamber, means for heating said still, back trap convertor, and expander chamber from the same products of combustion, and condensing apparatus leading from said dephlegmator.
6. An apparatus for treatment of hydro-carbon products comprising a still including a chamber for receiving a hydro-carbon material, heating means for said still, an expander chamber, a vapor line extending from said still chamber to the said expander chamber for conducting products of distillation from said still chamber to the expander chamber, means permitting heating of said expander chamber, a dephlegmator apparatus for receiving converted vapor products after treatment in said expander chamber, a rerun container for receiving heavier fractions from said dephlegmator positioned in communication with said expanding chamber, a source of superheated steam for flow into said still chamber and rerun chamber, a source of "fixed" gas for feeding into said rerun chamber, means permitting heating of said rerun container and condensing and

separating apparatus leading from said de-phlegmator.

7. The expansion process of refining hydro-carbon materials which consists in feeding a hydrocarbon in its vapor phase only from an area of a predetermined pressure into the lower end of a relatively large expansion compartment of a predetermined lower pressure to permit of a mechanical expansion of the hydrocarbon vapor as it enters the said compartment, subjecting the said hydrocarbon in its vapor phase only in said compartment to a heat treatment for expansion as the said vapor rises therein, contacting outside of a plurality of laterally spaced but substantially vertically arranged heating zones from which the heat radiates and along which the vapor passes from the lower end of the compartment to the upper

end thereof, and withdrawing from the upper end of said compartment the desired components of said vapor.

8. The process of treating hydrocarbons which consists in feeding a hydrocarbon in its vapor phase only into an expansion compartment at the lower end of said compartment, causing said vapor to vertically ascend in said compartment in an undivided mass, withdrawing said vapor from the top of said compartment, and during the vertical flow of the vapor through said compartment heat treating the same in its undivided mass condition at a plurality of closely spaced vertical heating zones radiating heat into said vapor mass capable of converting said vapors.

RUSSELL K. COLLINS.
